(57) **CLAIM**

The ornamental design for a throttle body, as shown and described.

DESCRIPTION

FIG. 1 is a front-right elevated view of a throttle body according to an embodiment of the new design;

FIG. 2 is a front-left elevated view thereof;

FIG. 3 is a front-right depressed view thereof;

FIG. 4 is a front-left depressed view thereof;

FIG. 5 is a rear-left elevated view thereof;

FIG. 6 is a rear-right elevated view thereof;

FIG. 7 is a rear-left depressed view thereof;

FIG. 8 is a rear-right depressed view thereof;

FIG. 9 is a front plan view thereof;

FIG. 10 is a rear plan view thereof;

FIG. 11 is a right-side plan view thereof;

FIG. 12 is a left-side plan view thereof;

FIG. 13 is a top plan view thereof; and,

FIG. 14 is a bottom plan view thereof.

All broken lines shown in the drawings are for environmental purposes only and form no part of the claimed design.

1 Claim, 12 Drawing Sheets
